(57) **CLAIM**

The ornamental design for a handle, as shown and described.

DESCRIPTION

FIG. 1 is a front perspective view of a first embodiment of a handle;

FIG. 2 is a front elevation view thereof;

FIG. 3 is a bottom plan view thereof;

FIG. 4 is a magnified transverse section view thereof taken along line 4-4 shown in FIG. 2; and

FIG. 5 is a magnified transverse section view thereof taken along line 5-5 shown in FIG. 2.

FIG. 6 is a front perspective view of a second embodiment of a handle;

FIG. 7 is a front elevation view thereof;

FIG. 8 is a bottom plan view thereof;

FIG. 9 is a magnified transverse section view thereof taken along line 9-9 shown in FIG. 7; and

FIG. 10 is a magnified transverse section view thereof taken along line 10-10 shown in FIG. 7.

FIG. 11 is a front elevation view thereof;

FIG. 12 is a front plan view thereof;

FIG. 13 is a bottom plan view thereof;

FIG. 14 is a magnified transverse section view thereof taken along line 14-14 shown in FIG. 12; and,

FIG. 15 is a transverse section view thereof taken along line 15-15 shown in FIG. 12.

The broken lines in the figures show environmental structures that form no part of the claimed design.

Top views of the above-mentioned embodiments are not shown, and no claim is made thereto.

1 Claim, 6 Drawing Sheets
